UNITED STATES PATENT OFFICE.

JESSE S. WENTWORTH, OF DECATUR, ILLINOIS, ASSIGNOR, BY MESNE ASSIGNMENTS,
TO UNITED SHOE MACHINERY CORPORATION, OF PATERSON, NEW JERSEY, A COR-
PORATION OF NEW JERSEY.

ASSEMBLING-MACHINE.

1,336,875.

Specification of Letters Patent. Patented Apr. 13, 1920.

Application filed March 27, 1914. Serial No. 827,596.

To all whom it may concern:

Be it known that I, JESSE S. WENTWORTH, a citizen of the United States, residing at Decatur, in the county of Macon and State 5 of Illinois, have invented certain Improvements in Assembling-Machines, of which the following description, in connection with the accompanying drawings, is a specification, like reference characters on the drawings indicating like parts in the several figures.

This invention relates to machines for use in the manufacture of boots and shoes and is herein shown as embodied in a machine for use in assembling the parts of 15 boots and shoes and for fitting such parts to the last preliminary to the pulling-over and lasting operations.

In the assembling operation as heretofore practised, it has been usual for the operator 20 to place the counter, box toe, upper and lining loosely about the last, arrange these parts in their correct relative positions, and then drive a tack through the middle part of the rear of the heel to temporarily secure the assembled elements of the shoe together.

These operations have either been performed by hand, or with the aid of a machine. In some instances it has been proposed to drive two anchoring tacks through 30 the assembled shoe materials, one at the back of the heel, and the other through marginal portions of the counter and upper which had been wiped over upon the inner- 35 sole at the center of the rear of the shoe. The use of a single tack at the back of the heel or of two tacks which were located substantially at the extreme rear end portion of the shoe to secure the assembled parts 40 of a shoe together I believe to be insufficient for this purpose. Under some other practices of assembling the upper was stretched longitudinally of the last with a view to fitting it to the lines of the last at the sides 45 and also in order to draw the upper and counter snugly against the heel end portion of the last. While there were substantial advantages gained over prior practices by this method some of the benefits due to 50 straining the upper lengthwise of the last were lost for the reason that no provision was made to anchor the upper at the sides of the counter following the longitudinal stretching. It is well known that the free

ends or wings of the heel stiffener have a 55 tendency to swing down between the upper and the side of the last during the operations preparatory to lasting and that the lasting machine operator usually is obliged to pull up these stiffener ends as an early 60 step in lasting the rear part of the shoe. It is highly desirable that some means be provided in the machine which performs the assembling operation for securing the stiffener ends against such displacement and 65 thereby saving the time of the lasting machine operator. It is also desirable that means be provided to obtain a snug fit of all of the upper materials to the side faces of 70 the last at the front ends of the heel stiffener at or in the neighborhood of the heel breast line, and that said upper materials be secured at these points in such manner as to maintain close relation to the last until 75 the completion of the lasting operation.

In order to overcome many of the objections heretofore found to exist in assembling machines, and furthermore to secure the result above referred to, a very important feature of this invention consists in a 80 novel construction and arrangement of means for seizing an upper at the forepart and stretching it in a direction lengthwise of the last, so as to strain the upper about the heel end and to cause it to closely conform to the lines of the last at the sides of the counter, and means for anchoring the upper to the last at the heel portion of the shoe in such manner as to maintain the stretched upper in close relation to the last at those 85 points where it is desirable that it should be snugly fitted. In the construction shown the upper at the forepart is preliminarily strained in a lateral, as well as a longitudinal direction relatively to the last, to the end that 90 it may be brought snugly up to all of the curves of the last at the fore part and stretched approximately into the position that it will finally assume in the finished shoe. To this end, in the herein illustrated embodiment of the invention, I employed three grippers, one of which is located at the toe end, and the others are located one on each side and at substantially the ball of the last. 95 These grippers are supported for movements, and are actuated, in outwardly divergent paths, the toe end gripper moving in a direction which is inclined upwardly and for-

wardly relatively to the toe end of the shoe, and the side grippers moving upwardly and laterally away from the opposite sides of the shoe bottom. To secure the best results in fitting the upper to the sides of the last the illustrated machine embodies means for pressing the upper and counter of the shoe against the last, at the sides, and at the rear end of the heel, and for wiping the marginal portions of the upper and counter over upon the innersole and securing them in position, while the upper is under lengthwise strain, such means for shaping the upper at and adjacent to the edge of the shoe bottom constituting a further feature of the invention the utility of which is obviously not limited to machines of the particular type illustrated. The pressing means may advantageously be in the form of yieldingly mounted pads which are located below and closely adjacent to the wipers so as to cooperate therewith in forming a well-defined edge on the upper and counter about the heel end of the shoe. For securing the upper and the counter in position the machine shown has means for driving fastenings through the wiped-over portions at the sides and at the end of the heel, the side fastenings being located substantially at the front ends of the side portions of the counter.

In the illustrated machine the last about which the parts of the shoe to be assembled are loosely arranged is supported on a pivoted jack and the grippers are supported upon a pivoted frame and said jack and frame are automatically carried, as an entirety, rearwardly while the upper is under the described lengthwise and lateral strain, and at the same time the pressing, wiping, and fastening mechanisms are moved forwardly to meet the shoe, and the upper and counter are pressed against the sides and rear of the heel. The shoe is then clamped, and the machine comes to rest in order to permit inspection of the shoe. When the machine is restarted the fastenings are driven, and the several parts are then returned to their former positions. The performance of these several operations, automatically and in sequence, insures uniformity in the appearance of the finished shoes, and saves labor on the part of the operator. I regard the mechanisms for accomplishing these results as important features of this invention.

Another important feature of the invention lies in the means for clamping, and unclamping the shoe. In the illustrated machine this is comprised in two down-holds, which are adjustably supported from a sliding member above the position occupied by the last when the jack is moved to the rear, and operating means, including a common actuating lever, which is yieldingly connect-

ed with both the jack and the down-holds. When the last is to be clamped, the actuating lever is moved by its cam in a direction to force the down-holds and jack yieldingly against the last, and upon a reverse movement of said lever the down-holds and jack are separated for unclamping the last. In connection with such mechanism, a manually-operable lever and connections are provided for permitting the operator to unclamp the jack and return it to the front of the machine in order that the shoe materials may be inspected and, if needs be, further adjustments of the upper about the last effected.

Other features of the invention, including important details of construction and combinations of parts, will be hereinafter more specifically referred to and claimed.

In the drawings:

Figure 1 represents a side elevation of a machine embodying the invention;

Fig. 2 shows the same machine in front elevation;

Fig. 3 is a detail view showing, diagrammatically, the mechanism for operating the jack and down-holds;

Fig. 3^a is a detail view showing, diagrammatically, the mechanism for controlling the operation of the staple drivers;

Fig. 4 is a perspective view of a presser, a heel seat wiper, and the staple forming and driving devices associated therewith;

Fig. 5 is a perspective view showing in detail on a slightly enlarged scale, and partly sectional, some of the parts shown in Fig. 4;

Fig. 6 is a detail view showing one of the anvils, and the end portion of a driver in position to cut off and drive a staple;

Fig. 7 is a view of a staple strip employed in connection with the stapling mechanism illustrated in Figs. 4 and 5;

Fig. 8 is a plan view, partly sectional, of the one-revolution clutch;

Fig. 9 is an end elevation of the one revolution clutch with the controlling devices therefor; and

Fig. 10 is a perspective, detail view, of the wedge for controlling the one-revolution clutch.

The machine frame 2 comprises a suitable number of upright members or standards and of transverse bracing members. The frame supports bearings for a shaft 4 which carries a loose pulley 5^a for receiving power through a belt from any suitable source. A gear 5 is fast to the power shaft 4 and meshes with a gear 6 which is fast to a shaft 7 and preferably has twice as many teeth as the gear 5 so that the shaft 4 will be rotated twice for each rotation of the shaft 7. The shaft 7 carries cams for effecting the operative movements of the several mechanisms of the machine.

In the preferred embodiment of the invention the starting and stopping of the power shaft 4 is effected through a one-revolution clutch, and as the geared connections between this shaft and the cam shaft 7 are in the ratio of 2 to 1 the machine is brought to a stop when the shaft 7 has completed a semi-rotation, and is re-started by a second depression of the controlling treadle to complete the cycle of operation.

Any suitable form of one-revolution clutch may be employed to secure this result. As shown in Figs. 8, 9 and 10, the loose pulley 5^a is provided with a series of holes 8 arranged circumferentially about the shaft 4. The shaft 4 has keyed thereto a frame 9 within which slides a spring-pressed pin 107 which is arranged to enter in one of the holes 8 in the loose pulley to clutch the latter to the shaft. An arm 108 is pivotally connected at one end to the frame 9 and is provided with a square recess which receives a nut 110, said nut being affixed to the clutch pin 107, and being mounted for pivotal movement in the recess of the yoke by screws provided with set nuts, as shown in Fig. 9. The outer free end of the arm 108 is deflected laterally as shown in Fig. 8, and is also beveled to coöperate with the beveled end 111 of a bell crank wedging member 112 which is pivoted at 113 to a rigid part of the frame of the machine. The arm 114 of the wedging member carries a pawl 115 which is normally held by a spiral spring so that its free end rests against the ledge 116 projecting rigidly from the arm 114 of the wedge member. The controlling treadle 117 is fulcrumed to the frame of the machine, and a rod 118 extends from its inner end to a bell crank 120 which is pivoted to the frame of the machine. The upper end of the bell crank 120 is slotted to receive a pin 122 projecting laterally from a slide 124 which is guided for movements in suitable ways on the frame of the machine. A spring 126 forms a connection between the upper arm of the bell crank 120 and the frame of the machine and normally acts to maintain the bell crank and slide to the rear, and the controlling treadle 117 in elevated position, as shown in Figs. 1 and 9. The pin 122 extends through the slide 124 and over the pawl 115 so that when the treadle is depressed and the slide moved toward the front of the machine the pin will act to depress the arm 114 of the wedging member 112 and thereby move its end 111 away from the free end of the arm 108 and permit the pin 107 to enter one of the holes 8. A spiral spring 128 connects the arm 114 of the wedging member with a bracket or other fixed part of the machine frame and acts with a normal tendency to rock the wedge member so as to locate its beveled end 111 in the path of movement of the free end of the arm 108. A rubber buffer

130 is located below the beveled portion at the upper free end 111 of the wedging member and when the machine is brought to a stop the coöperating beveled surfaces of the member 111 and arm 108 are in engagement 70 and the end of the arm rests on the rubber buffer. In this position of said parts the locking pin 107 is withdrawn from clutching engagement with a hole 8 in the loose pulley 5^a, and hence said pulley turns freely on the power shaft 4. When the treadle 117 is depressed, however, the pin 122 on the slide 124 is moved against the upper inclined surface of the pawl, thereby turning the wedging member 112, disengaging its upper free 80 end from the arm 108, and permitting the spring-pressed pin 107 to enter one of the holes 8 to clutch the loose pulley to the power shaft 4. When the pin 122 has traveled over the pawl 115 the spring 128 will 85 return the wedging member to its normal position with its end 111 in the path of the free end of the arm 108, so that when the shaft 4 completes a rotation the arm 108 will reengage the wedging member, the locking 90 pin will be withdrawn from the hole which it occupied in the loose pulley, and the main shaft 4 will be brought to rest. When the treadle 117 is released by the operator the spring 126 will effect a rearward movement 95 of the slide carrying the pin 122 which latter will return to its starting position, the pawl 115 being lifted by the pin during such movement. A stop pin 132, which is rigidly connected to the frame of the machine, lies 100 in the path of movement of the ledge 116 and by its engagement therewith limits the upward movement of arm 114 of the wedge member when said member is returned to position for unclutching the pulley from the 105 shaft by the spring 128. Features of this starting and stopping mechanism are claimed in a divisional application Serial No. 257,727, filed on October 11, 1918.

The last upon which the parts of the shoe 110 are to be assembled is preferably supported upon a jack 48 which carries at its upper end a pin to enter the usual jack pin socket of the last. The jack is shown as being pivotally sustained at 21 upon a bar 47 which 115 is mounted to slide in suitable guideways which may be conveniently carried by a portion of the main frame of the machine, as shown in Fig. 1. The lower portion of the bar 47 is provided with a plurality of 120 holes, whereby it may be pivotally connected, with capacity for adjustment, with the end of the jack-operating lever 46. The lever 46 is fulcrumed by a pin 46^a to a block 125 which slides on a guide rod 46^b projecting rigidly from a horizontal member of the machine frame. The fulcrum block is located between two spiral springs 49, one of which is confined between said block and said frame member, and the other between the 130

block and a nut which is secured to the outer end of the rod 46^b, the latter of these springs being stronger than the former. The rear end portion of the lever 46 is shown as being curved upwardly and at the extremity thereof it carries a cam roll 45 which rests upon a cam 145, designed as shown in Fig. 3 of the drawings. An extended portion of the lever 46, beyond the roll 45, has connection with one end of a strong spiral spring 450, the opposite end of this spring being connected to a rigid portion of the frame, and the spring acting to hold the roll in yielding engagement with the cam. In Fig. 3, the roll is shown as resting on the highest portion of the cam in which position the lever 46 has its forward end lowered, thereby holding the jack 48 depressed. A continued rotation of the cam 145 in the direction indicated by the arrow will permit the roll 45 to pass from the high to the low point of the cam, thereby permitting the spring 450 to move the jack from its lower position as shown in Figs. 1 and 3, to its upper position, as will be more fully explained hereinafter.

At a suitable point above its connection with the bar 47 the jack 48 is provided with a plurality of holes, to one of which is pivotally connected a link 22, the opposite end of which link is pivotally connected to one arm of a bell crank 24. The pivotal connection between the link 22 and the bell crank 24 is capable of adjustment as the bell crank 35 is provided with a plurality of holes which are respectively located different distances from the fulcrum of the lever. The lower arm of the bell crank 24 carries a roll 26 which has engagement with a cam 28 fast on the cam shaft 7, and an extension from the arm of the bell crank 24 is connected with the upper end of a strong spring 260 whose lower end is secured to the frame of the machine, said spring acting to hold the roll 26 in yielding engagement with the cam 28. This cam is so designed that, at the proper time in the cycle of operation of the machine, the roll 26 by passing down to the low part of the cam will, through the bell crank 24 and links 22, swing the jack 48 rearwardly so as to carry the last and upper materials thereon from the position shown in Fig. 1 of the drawings, to a rearward position, for a purpose to be hereinafter explained.

The jack 48 has a rigid forward extension 134 which is provided with an opening or guideway to receive a bar 10 for supporting the three grippers which are preferably employed in this machine, one gripper being located at the extreme end of the toe, and one on either side of the shoe, at a point approximately opposite the ball. The upper end portion of the bar 10 is provided with a block 10^a which rests upon the extension

134 of the jack. Knuckles 136 having pins which turn freely in sockets in the block 10^a are provided, one at the front of the block, and one on each side thereof, as shown in Fig. 1. Rods 138 are pivotally connected at their lower ends with the knuckles 136, the upper ends of these rods carrying plates 140 to which rods 142 are pivoted, said rods being adjustable through clamping bolts 144, which pass through segmental slots at the upper portions of the plates 140. Suitable gripper carriers 146 are adjustably secured to the rods 142 by set screws 148. The gripper carriers sustain grippers 150 which latter may be of any desirable construction, but as herein shown comprise members which are independently pivoted to their carrier and have engaging jaws, and handles, with springs interposed between the handles and acting to yieldingly force the jaws together. These grippers are opened by hand to disengage the upper materials of a shoe, and are closed automatically by their springs to engage the upper materials when the handles are released.

The supporting devices for the grippers are constructed and arranged in such manner as to hold the three grippers in divergent relation to the shoe supported on the jack 48 in order that the upper when engaged by the grippers may be held in outspread relation to the last. As shown in Fig. 1, the supporting rod 138 for the toe end grippers is inclined forwardly relatively to the bar 10, and also to a line perpendicular to the plane of the shoe bottom when a shoe is on the jack, and is connected by a rod 152 with an arm 154 which is pivoted to the jack 48. A spiral spring 156 is confined between a collar on the rod 152 adjacent the forward end of the arm 154, and a washer which bears against the rod 138 for supporting the toe gripper. By this means the toe gripper support is yieldingly maintained in a forwardly inclined relation to the frame of the machine. The side grippers supports are similarly maintained in an outwardly divergent relation to the vertical median line of the machine by suitable struts 160 which, as shown in Figs. 1 and 2, extend from the side grippers supporting rods 138 to the supporting rod for the toe end gripper, and are yieldingly connected to the latter by springs 162 which are confined between blocks carried by the toe gripper rod 138 and nuts on the ends of the struts 160.

The bar 10 is pivotally connected with a rod 162 having thereon a spiral spring 164 which is confined between a collar 162^a rigidly secured to the rod and a collar 162^b which slides on the rod, and is provided with a pin which enters a slot at the outer end of a lever 12, fulcrumed at 165 to a bracket depending from the frame of the

machine. The rear end of the lever 12 is provided with a plurality of holes to form an adjustable, pivotal connection with the link 14, whose opposite end is pivotally connected, with similar capacity for adjustment, with the end of a lever 16 which is fulcrumed to the frame of the machine and at its rear end carries a roll 18 which engages a cam 20 fixed to the cam shaft 7. An extension of the lever 16 is connected with one end of a strong spring 266 whose opposite end is fastened to the frame of the machine, said spring acting to hold the cam roll 18 in yielding engagement with the edge 10 of the cam 20. This cam is so designed that, at the proper time in the cycle of the machine's operation it will, through the described connections including the spring 164, yieldingly raise the bar 10 and the several grippers and, by reason of the forwardly inclined relation of the toe gripper rod 138 and the laterally inclined relation of the side gripper rods 138 to the path of movement of bar 10, exert an upward and 20 outward pull upon the upper materials which have been seized by the grippers, to hold such materials in an outspread condition. The forward component of the pulling force which is applied to the toe end 25 gripper through the described construction serves to strain the upper longitudinally of the last, and to maintain it in close relation to the sides of the last so that it fits snugly the curves of the last.

Referring again to the jack-controlled mechanism, a shaft 166 is suitably mounted in bearings in the main frame of the machine, and rigid therewith is a handled lever 104 which projects toward the front 30 of the machine and in convenient position for manipulation by the operator. An arm 168, also rigid with the shaft 166, projects toward the front of the machine, and at a suitable angle to the handled lever 104. The 35 arm 168 overlies an extension of the pin 21 which pivotally connects the jack 48 with the bar 47 and may, by a suitable movement of the lever 104, be made to engage the pin when the jack is in an elevated position. Another arm 170 projects rigidly from the shaft 166 and is located in position to engage the rear portion of the jack 48, upon depression of the lever 104. By this construction the operator is enabled to 50 effect a manual depression of the jack when it is raised, and additionally may move the jack from its rearward position,—to which it was moved through the cam 28 and connections as above described, to a forward 55 position, when desired. During such manual depression of the jack the lower spring 49, and the spring 450, or either of these springs, will yield suitably to permit such movement. It will also be seen that as the 60 grippers carrying frame is connected with

the jack by the extension 134, the grippers will follow the movements of the jack when the latter is carried from its position as shown in Fig. 1, to its rearward position, and vice versa. On the other hand, as the 70 bar 10 slides vertically in the aperture through the extension 134 the grippers carrying frame is capable of movement vertically independently of the jack to permit the grippers to be raised for exerting a pull 75 on the upper to draw the upper materials against the heel end of the last, and along the sides of the last, so that the upper will be snugly fitted to the lines of the last and the tendency to spring away from the sides 80 of the shoe will be prevented.

Referring to Figs. 1 and 3, the rear portion of the frame of the machine is provided with a standard 172 having therein a vertical groove 174, and a slide 71 carries 85 a rib fitting the groove to thereby guide the slide vertically. The slide 71 is attached to the lever 46 by a rod 176 provided near its lower end with a fixed collar 178, the lever 46 being connected by a pivot 50 with a 90 sliding block 177 which is normally forced against the collar by a spring 180, the latter being confined between the block and a retaining nut 181 which is threaded to the 95 lower end of the rod 176. The upper portion of the slide 71 is provided with a transverse aperture which receives a bar 182, and a suitable clamping screw 183 secures the bar to the slide with capacity for adjustment in the aperture in a direction transverse to the slide. Secured to the forward end of the bar 182 is a down-hold 105, which is arranged to engage the rear portion of the last bottom for clamping the last to the jack when the slide 71 is depressed. The upper portion of the down-hold 105 is provided with a transverse aperture to receive, adjustably, a rod 184 which is clamped to the down-hold 105 by a set screw 105^a. The forward end of the rod 110 184 is provided with a vertical aperture to receive, adjustably, a second down-hold 30, a suitable set screw 30^a being threaded in an aperture at the forward end of the rod 184 to adjustably clamp the down-hold 30 in 115 position. When the jack with a shoe thereon has been moved to its rear position, as indicated by dotted lines in Fig. 3, the down-hold 30 will be directly over the fore part of the last, while the down-hold 105 120 will be directly over the heel portion of the last, and by the described adjustments the down-holds may be arranged at the appropriate relative heights, and at such distance apart in a direction longitudinally of the 125 last, to engage with the last bottom at suitable points to effect a rigid clamping of the last and the shoe thereon against the jack when the jack and down-holds are moved toward each other. It will be seen 130

that when the cam roll 45 passes from the high point of the cam 145 to the low point thereon the upward movement of the front end of the lever 46 will raise the jack, while 5 the downward movement of the rear portion of the lever will simultaneously depress the down-holds and thus firmly clamp the shoe in position to receive the fastenings which will be thereafter driven through 10 the upper materials at the heel end of the shoe to secure such materials in finally assembled condition on the last. The described movements of the jack and down-holds will be effected yieldingly through 15 the springs 49, 180 and 450.

Extending rearwardly from the frame of the machine is a rigid bracket 186 which through a pin sustains a link 187 having at its upper end an angular extension in 20 which is a segmental slot, and a clamping screw 189 passes through the slot and is threaded into the bracket. The lower end of the link 187 is pivotally connected to the back gage 190 which extends toward 25 the front of the machine and is there provided with a laterally curved portion shaped to receive the rear face of the heel portion of a shoe. A link 191, arranged substantially parallel with the link 187, and 30 also pivotally connected to the bracket and back gage, but at points in advance of the link 187, coöperates with the latter in effecting a parallel-movement connection between the back gage and its supporting bracket. 35 Upon loosening the clamp screw 189 the back gage may be adjusted to proper position for receiving the rear part of the shoe when the latter has been moved with the jack to its rearward position, and preliminary to the insertion of the fastenings.

In the illustrated embodiment of the invention the upper, lining, and counter are wiped over upon the bottom of the heel portion of the shoe at three separate points, 45 namely, at the center of the rear of the heel, and on each side of the shoe at points substantially in line with the breast of the heel. In order to effect the desired inward wiping, and the securement of the over-wiped shoe materials at these points, the 50 machine is provided with three wipers, and with associated staple-forming and driving mechanisms. A pad is coöperatively associated with each wiper and is constructed 55 and arranged to yieldingly press the upper materials against the edge of the last as the wiper is advanced to wipe the upstanding materials over and down upon the shoe bottom. One of the staple forming and 60 driving mechanisms and its associated wiper and pad are shown in Figs. 4 to 7, and the arrangement of the several wiping and fastening mechanisms relatively to each other is best shown in Figs. 1 and 2.

65 The machine frame is provided with two

laterally extending brackets 192, and a rearwardly extending bracket 193, to which are connected links 42, the latter being in turn pivoted at their upper ends to the rear end portions of suitable raceways 41^a, having 70 thereon raceway covers 41 which are adjustably secured to the raceways by screws 410, which are threaded into the raceways and pass through inclined slots in the raceway covers. In this way the covers are capable of being clamped at different distances 75 from the tops of the raceways in order to accommodate suitable staple strips of varying degrees of thickness. The forward portions of the raceways 41^a are provided with 80 molding surfaces comprising a plurality of oppositely beveled portions 41^b, 41^c, whose angular relation to each other progressively increases toward the end of the raceway, and extending from the forward one of these 85 several molding surfaces is an anvil 194, having the formation of a flat strip of metal and which extends part way into the driving aperture 196 formed in the staple driving tube which terminates in a nozzle to be 90 located over the edge of the shoe. A driver 198, rigid with a driver rod 198^b, and having a flattened portion 198^c is supported for reciprocating movements in the aperture 196, and a spiral spring 199 is confined between a nut at the lower end of said driver 95 tube and a sliding collar 200, which is located near the upper end of the tube and is secured by a pin 200^a to the driver rod. The upward movement of the sliding collar 100 200 is limited by a stop collar 201 which is adjustably secured to the driver rod guiding tube. The upper extremity of the driver rod is provided with a head 202, as shown. Secured to the sliding collar 200 is a staple 105 former, comprising three members, two of which, 41^a and 41^c, are shaped to correspond, respectively, with the molding surfaces 41^c and 41^b, and the third one, 41^b is shaped to fit over the anvil 194. The construction and 110 arrangement of the staple former members and the staple molding surfaces and anvil are such that they will act, successively, to bend the staple portions of a flat staple strip S, such as shown in Fig. 7, as the same is 115 fed toward the driver, into U-shaped staples of the form shown in Fig. 6. A staple strip feeder, comprising a bifurcated pawl 203, which is pivotally supported on the lower end of a lever 204 pivoted in turn to a 120 bracket on the raceway, is operatively controlled by the movement of the staple former, the relation of the parts being such that when the driver rod is forced downwardly the pawl will be carried to the rear 125 and move over the strip of staples, but as the driver rod rises a forward movement will be imparted to the pawl to advance the strip toward the driver a distance equal to the width of one staple. A retaining pawl 130

- 205 is yieldingly forced against the strip of staples and acts to prevent retrograde motion thereof during the backward movements of the feeding pawl 203. Assuming
- 5 a completely formed staple to have been fed, through the advance of the staple strip, into the position shown in Fig. 6 where it projects beyond the forward end of the anvil 194, and into the aperture 196, and the
- 10 succeeding portions of the staple strip being in various degrees of formation, as shown in Fig. 4, when the driver is actuated downwardly its forward edge will sever the leading staple from the strip and drive it
- 15 through the driver aperture 196 and into the upper materials which have been wiped over upon the bottom of the shoe. The same movement of the driver will cause the staple formers 41^a, 41^b and 41^c to coöperate with
- 20 the anvil and molding surfaces at the end of the raceway in the formation of other staples, which latter will be successively formed, cut off, and driven into the work upon the succeeding downward movements
- 25 of the driver.
- Each of the wipers 70 is pivotally connected near its forward end to a lug 206 depending from a raceway, and preferably has a convexly-curved, beveled lower surface so
- 30 as to turn smoothly the upstanding upper and counter at the heel of the shoe over upon the innersole. Each wiper is located below a staple nozzle and is provided with an aperture to receive the nozzle. The rear end of
- 35 the wiper bar is perforated to receive a guiding rod 208, which is threaded into the raceway and has an adjustable stop nut 209 for limiting the upward, pivotal movement of the rear end of the wiper and the consequent
- 40 extent of normal depression of the front end of the wiper relatively to the plane of the shoe bottom. A spring 214 is confined between the lower surface of the rear end portion of the wiper and a head 211^a at the
- 45 lower end of the rod. The pad 44 for engaging the edge portion of the shoe adjacent each wiper is carried by the forward end of a rod 207 which is guided in holes formed in two lugs projecting from the wiper, a spring
- 50 208^a being confined between the pad and one of said lugs for yieldingly urging the pad toward the shoe. The pads 44 are preferably of rubber, felt, or other soft or elastic material to prevent marring of the upper.
- 55 The three staple forming and driving mechanisms together with their associated heel seat wipers and pads are, at the proper time in the cycle of the machine's operation, moved simultaneously toward the heel end
- 60 of the shoe, two of said mechanisms being caused to engage the shoe at points substantially in line with the breast, and the third at the central portion of the rear of the heel. To secure this operation three levers 40 are
- 65 provided which are fulcrumed at 400 to the
- frame of the machine on pivot pins arranged, respectively, to permit two of the levers to move in opposite directions laterally, and the third lever to move longitudinally of the machine, and said levers have
- 70 pivotal connections 210 between their forked upper ends and the wipers 70 at points to the rear of the pivots 206. The lower ends of the levers 40 are pivoted to blocks
- 75 211 that slide vertically on guide rods 38, depending from a spider 36, which is mounted for vertical sliding movements in the frame of the machine. Spiral springs 37 surround the rods 38 and are confined between the spider and the top of each block 211, and
- 80 provide yielding connections between the spider and the levers 40, and stop collars 40^a are secured at the ends of the rods for retaining the blocks 211 thereon. A rod 35 secured to the spider 36 is provided with an
- 85 adjustable, rigid collar 212 having a pin which is engaged by the forked end of a lever 33, fulcrumed to the machine frame and having its opposite end connected with the strap 32 of an eccentric 31 which is fast
- 90 to the cam shaft 7. By this construction, when the cam is rotated in a manner to cause its strap to raise the rear end and depress the forward end of lever 33 the spider will be moved down and through its connections
- 95 with the levers 40, which include springs 37, will yieldingly actuate these levers so as to move their upper end portions and the wipers and stapling mechanisms carried thereby from the positions shown in Figs. 1-2 to
- 100 100 the positions where the wipers will engage and wipe in the upper materials about the heel end of a jacked shoe. Subsequently, upon further rotation of the cam the spider will be raised until, through engagement of
- 105 collars 40^a with the blocks 211, the levers 40 will return the wipers and staple mechanisms to their positions as shown in Figs. 1 and 2. Following the described inward movements of the wipers and staplers the
- 110 drivers will be actuated to drive staples and secure the overwiped material,—including the counter and upper,—to the innersole, it being understood that the wipers and pads will be retained in engagement with the shoe
- 115 until the fasteners are completely driven. This result is secured by the sliding connections between the blocks 211 and spider 36, the springs 37, and the eccentric 31, as the lost motion between the spider and blocks
- 120 is sufficient to permit the staples to be completely driven into the shoe before the eccentric has elevated the spider far enough for the collars 40^a to engage the blocks and effect reverse movements of the levers 40. It
- 125 will be seen that the upper arms of the levers 40 and the links 42 constitute, with the raceways and the supporting base for the levers and links, parallelograms which insures that the stapling mechanisms will be
- 130

advanced into driving positions in planes substantially parallel with the shoe bottom. In view of the fact, however, that the wipers and pads have connections with staplers by pivots 206, and with the levers 40, by pivots 210, they may rock to adapt their positions to the contour of the last, the springs 214 yielding to permit such movements. In practice the nuts 209 are preferably so adjusted that the forward ends of the wipers first engage the upper at points slightly below the edge of the last bottom and are caused to ride up and over the edge of the last by the pressure of engagement between the last and the beveled and curved surfaces of the wipers, the adjustability of the nuts, however, permitting the normal relation of the wipers to the plane of the shoe bottom to be varied to cause them to encounter more or less resistance in their operative movement, as may be required by the character of the shoe materials. During the upward movement of the forward ends of the wipers they assume inclined positions and their rear ends are depressed thereby compressing the springs 214, and when their wiping portions clear the edge of the last the springs 214 cause the wipers to act yieldingly on the upper, the wipers being then advanced over the edge of the last to wipe the upper and counter flat down upon the innersole. During this operation the pads 44 engage yieldingly the sides and end of the last and press the upper tightly against the immediately adjacent points where the wipers are acting. The wipers and pads thus coöperate in forming a sharp angular edge of the upper and counter about the heel portion of the last. While in the embodiment of the invention as herein illustrated and described I show only three wipers and pads with their associated staple-driving devices, it is to be understood that if desired a greater number of these instrumentalities may be employed, and that the wipers and pads may be sufficiently close to each other to completely last the heel seat of a shoe.

The several staple driver rods are simultaneously actuated by a hammer 106 which is provided with a rectangular guiding aperture to fit over and slide vertically upon the down-hold 105, the latter being formed of rectangular cross-section. The hammer is connected by a link 112 with a driver arm 74, which is pivoted to the bracket 186 and is driven by a strong spring 75. The driver arm has a slot as indicated by dotted lines in Fig. 1 within which is journaled a roll 216. A slide 81, which has a projection to enter a vertical groove 217 formed in the standard 172, whereby it is guided for vertical movements, carries at its upper end a bifurcated projection 82 carrying two rolls 82^a located

below the arm 74. The forks of this projection are located, respectively, on each side of an L-shaped trip pawl 72 pivoted to a bracket rigid with the frame. The pawl has a vertical arm which is arranged to be located at times, under the roll 216 to hold the driver arm and hammer in raised position, a spring 218 acting upon a horizontal arm of the pawl and forcing its end against a hooked projection 220, (see dotted lines Fig. 1) formed in a part of the frame of the machine, to maintain the pawl in such position. An arm 120 is connected with the projection 82 of the slide 81 and extends through the slot in arm 74 to a point above the arm where it carries a roll 120^a which overlies the horizontal arm of the trip pawl. A rod 80 connects the slide 81 adjustably with the slotted portion 76^a of a lever 76, which lever is fulcrumed at one end to a bracket rigid with the frame and carries at its opposite end a cam roll 78. The cam roll rests upon a cam 79 which is fast to the shaft 7, and is provided with a dropped portion D. A strong spring 222 is connected at one end with the lever 76, and at its opposite end to the machine frame and holds the cam roll in yielding engagement with the cam. When the several drivers have been positioned over the edge of the heel portion of an assembled shoe the driver rod heads 202 will be beneath the hammer 106, and the hammer and its actuating mechanism will occupy the positions shown in Fig. 3^a, with the hammer bar sustained upon the end of pawl 72, the driving spring 75 being then under tension and the cam roll 78 resting upon the high part of the cam 79. Upon rotation of the cam the roll will finally reach the dropped portion D thereof and the lever 76 and parts connected therewith will be pulled down by the spring 222, causing the roll 120^a to engage and trip the pawl 72 and thus permitting the hammer to descend under the influence of its spring and actuate the staple formers and drivers. Upon a continued rotation of the cam, the roll 78 will pass gradually from the lowest to a high point thereon, lifting the slide 81 and causing the rolls 82^a to engage and lift the hammer arm 74 against the stress of its spring until the roll 216 passes above the upper end of pawl 72, when the pawl will be moved beneath the roll by its spring, and will retain the hammer in elevated position, as shown in Fig. 3^a.

Features of the mechanism herein disclosed for forming and driving fasteners are claimed in a divisional application Serial No. 257,728, filed on October 11, 1918.

In the use of a machine, an upper, lining and heel stiffener are first placed loosely over a last to which has been applied an innersole, and the last is located on the jack pin of the jack 48 when the several parts of the machine occupy the positions in which

they appear in Fig. 1, the jack being depressed, and with the grippers, being tilted forward so that the upper materials are presented conveniently for the operator to effect 5 the necessary adjustments thereof to the lines of the last. The upper materials are then carefully arranged about the last in the positions which they are to occupy in the finished shoe, and the grippers 150 are 10 opened by hand, and then permitted by their closing springs to grip the upper at the end of the toe and at the two sides of the shoe, as shown in Fig. 1. The operator then steps on the starting treadle 117, withdrawing the 15 wedge 111 from engagement with the arm 108, thus permitting the loose pulley to be clutched to the driving shaft and starting the machine. Thereafter, through the cam 20, roll 18, lever 12 and spring 164, the grippers frame will be raised, causing the grippers to exert through the spring 164 a yielding pull upon the upper which will be pulled upwardly and slightly outwardly at the forepart of the last, the longitudinal strain 25 effected by the toe end gripper causing the upper to be drawn snugly about the heel end, and close in along the sides of the heel. The direction of the pull which will be exerted by the grippers is such that the upper materials will be fitted to the sides of 30 the last in a manner to prevent the formation of any wrinkles or bagginess, and particularly along the shank. Following the described pulling of the upper to the lines 35 of the last the jack carrying the last and upper materials, together with the grippers and their supports, will be moved, as an entirety, and while the upper is held by the grippers, from their positions as shown in 40 Fig. 1, toward the rear of the machine until the heel end of the shoe meets the curved portion of the back-rest 190, the last being then located beneath the two down-holds. Simultaneously with the rearward movement 45 of the shoe the wipers 70, pads 44, and their associated staple forming and driving devices are moved inwardly toward the shoe, the wipers engaging the upstanding upper and counter at the rear end of the heel 50 and at the two sides opposite the breast line and bending these materials over and wiping them down upon the innersole, and the pads pressing the materials firmly against the side and end portions of the last. The roll 55 45 thereafter passes from the high to the low part of the cam 145 and, through the described connections, raises the jack with the shoe thereon and the grippers-carrying frame, and simultaneously depresses the 60 down-holds 30 and 105. The shoe is thus pressed firmly against the wipers to effectually flatten the overwiped material down upon the heel seat portion of the innersole, and is also securely clamped between the 65 jack and down-holds in position to receive 70 the fastenings. At this point the driving shaft 4 will have made one complete rotation and the end of the clutch-actuating arm 108 will engage the beveled portion 111 of the wedging member 112, thereby unclutching 75 the shaft from the loose pulley and bringing the machine to a stop. Opportunity will then be afforded the operator to inspect the shoe so as to determine if the upper materials are properly positioned on the last, and to make any required adjustments of the upper to the lines of the last before the fastenings are driven. If it is desired at this stage to temporarily relieve the shoe 80 from the clamping engagement between the jack and down-hold, the operator will pull down on the handle 104, thereby depressing the jack and tilting it forward toward the front of the machine, the springs 49, 450 and 260 yielding as the rolls 45 and 26 are lifted 85 off of their cams. The upper and other shoe materials may then be adjusted, and upon the release of the handle, the jack will automatically return the shoe to its clamped position. Having satisfied himself that the 90 parts of the shoe are properly assembled, the operator then depresses the treadle a second time and starts the machine. The cam 79 having previously elevated the slide 81 and, through the rolls 82^a, raised the hammer arm 95 74 and placed the driver spring under tension, and the arm having been retained in such position by the pawl 72, as shown in Fig. 1, upon further rotation of the cam the pawl 100 will be tripped, and the staple drivers actuated to drive staples through the overwiped upper of the shoe. Thereafter the several parts of the machine will be returned to their original positions, as shown in Fig. 1, and the machine brought to a stop with the 105 jack presenting the assembled shoe to the front of the machine in order that the operator may remove the shoe and insert in the machine another last with the upper materials thereon, and the above-described 110 cycle of operations will be repeated. 115

The present invention is not to be limited to the specific embodiment thereof above described, and the right is reserved to make such changes in the construction, form or relative arrangement of the various details as would be fairly within the contemplation of the following claims. It will also be recognized that many of the features of the invention are not limited in utility to machines for assembling the parts of shoes but are broadly applicable to various machines 120 for use in shoe manufacture.

Having thus described my invention, what I claim as new and desire to secure by Letters Patent of the United States is:—

1. In an assembling machine, the combination with means for gripping an upper at the end and sides of the fore part of a last and stretching it lengthwise of the last, 125

- of means for simultaneously securing the upper to the innersole at points on opposite sides of the shoe located substantially in line with the heel breast. 65
5. 2. In an assembling machine, the combination with means for gripping an upper at the toe end and on opposite sides of the fore part of a last and stretching it longitudinally of the last, of means for simultaneously driving fastenings through the upper while under strain at points on opposite sides of the shoe located substantially in line with the heel breast. 70
10. 3. In an assembling machine, the combination with means for gripping an upper at the sides of the fore part of a last and stretching it along the sides of the last, of means for bending individual, separated portions of the upper and counter over upon the innersole at points located substantially at the forward ends of the counter, and means for driving fastenings into said bent over portions of the upper and counter. 75
15. 4. In an assembling machine, the combination with means for gripping an upper at the toe end and on opposite sides of the fore part of a last and stretching it lengthwise of the last, of means for wiping the upper over upon the innersole at three separated places located, respectively, at the heel end and at two opposite points on the sides substantially in line with the heel breast while the upper is under lengthwise strain, and means to secure the overwiped upper to the innersole. 80
20. 5. In an assembling machine, the combination with means for gripping an upper at the forepart and at each side of a last and stretching it lengthwise of the last, of means for pressing the upper against the sides of the heel end portion of the last while it is under lengthwise strain and for bending the upstanding portions of the upper over upon the last, and means for simultaneously driving fastenings into the bent over portions of the upper. 85
25. 6. In an assembling machine, the combination with means for gripping an upper at the fore part and at each side of a last and stretching it longitudinally, of means for pressing individual, separated portions of the strained upper against the sides of the last at two points located substantially in line with the heel breast and for wiping the upstanding portions of the upper over upon the innersole at said points, and means for driving fastenings through the overwiped upper. 90
30. 7. In an assembling machine, the combination with means for gripping an upper at the sides of the fore part of a last and stretching it lengthwise of a last, of means of yieldingly pressing separated, independent portions of the strained upper against the sides of the last at points substantially opposite the breast line and at the rear end of the heel and for wiping separated portions of the edge of the upper and counter over the last at said points, and means for driving fastenings through the overwiped material. 95
35. 8. In an assembling machine, the combination with means for gripping an upper at the sides of the fore part and for straining it lengthwise of a last, of upper overwiping and fastening inserting mechanisms constructed and arranged to move inwardly toward the edge of the last from opposite sides of the counter and at the rear end of the heel and to wipe the upper over upon the innersole and secure it in overwiped position, and actuating means for said mechanisms. 100
40. 9. In an assembling machine, the combination with means for gripping an upper at the sides of the fore part and for straining it lengthwise of a last, of upper overwiping and fastening inserting mechanisms constructed and arranged to move inwardly toward the edge of the last from opposite sides of the counter and at the rear end of the heel and to wipe the upper over upon the innersole and secure it in overwiped position, and actuating means for said mechanisms. 105
45. 10. In an assembling machine, the combination with means for gripping an upper at the toe end and on opposite sides of the fore part of a last and for straining the upper lengthwise of the last, of upper overwiping and fastening inserting mechanisms, means to move said mechanisms inwardly toward the edge of the last from opposite sides of the counter and at the rear end of the heel to wipe the upper over upon the innersole, and means to actuate the fastening inserting mechanisms for driving fastenings into the overwiped upper. 110
50. 11. In an assembling machine, the combination with means for gripping an upper at the sides of the fore part of a last and for straining the upper lengthwise of the last, of means for exerting pressure against the strained upper at the shank to cause the upper to fit closely to the lines of the last, and means acting while said pressure exerting means is in operation for driving fastenings through the upper and innersole adjacent to the points where the pressure is applied. 115
55. 12. In a machine of the class described, the combination with means for seizing an upper at the sides and end of the fore part and for straining it lengthwise of a last, of means for pressing the strained upper against the last at the shank and at the end of the heel to cause the upper to fit closely to the lines of the last, means for wiping the upper over upon the innersole opposite the

points where said pressure is applied, and means for driving fastenings through the overwiped upper.

13. In a machine of the class described, 5 the combination with means for seizing an upper at the sides of the fore part and for straining it lengthwise of a last, of a plurality of upper - pressing, overwiping and fastening - inserting mechanisms, each of 10 said mechanisms constituting an independent unit, and said mechanisms being respectively constructed and arranged to move in different directions toward the heel end of the last and operating to press the upper 15 against the last on each side of the heel and at the end of the heel, to wipe the edge of the upper over upon the last, and to secure the overwiped upper in position, and actuating means for said mechanisms.

14. A machine of the class described having, in combination, means for supporting a last in inverted position with an upper arranged loosely thereon, devices for seizing the upper at the fore part and for holding 25 it in an outspread condition, means for moving the last and upper-seizing devices as an entirety rearwardly while the upper remains outspread, a plurality of wipers, and means for moving said wipers toward the sides and 30 end portion of the heel of the last to wipe the upper down upon the innersole.

15. A machine of the class described having, in combination, means for supporting a last in inverted position with an upper arranged loosely thereon, devices for seizing the upper at the end and sides of the fore part and for straining it lengthwise of the last, means for moving the last and upper-straining devices as an entirety toward the 35 rear of the machine while maintaining the strain on the upper, a plurality of wipers, means for moving said wipers toward the sides and end portion of the heel of the last to wipe the upper down upon the innersole, 40 and means for driving fastenings to secure the upper in position.

16. A machine of the class described having, in combination, means for supporting a last in inverted position with an upper arranged loosely thereon, devices for seizing the upper at the sides of the fore part and for straining it lengthwise of the last, means for moving the last and upper-straining devices as an entirety toward the rear of the 45 machine, a plurality of pressing and wiping devices arranged to move toward the opposite sides and the end portion of the heel and acting to press the upper against the last and to wipe the upstanding edge of the 50 upper down upon the innersole, and actuating means for said devices.

17. A machine of the class described having, in combination, means for supporting a last in inverted position with an upper arranged loosely thereon, devices for seizing 55

the upper at the sides of the fore part and for straining it lengthwise of the last, means for moving the last and upper-straining devices as an entirety toward the rear of the machine, a plurality of upper-pressing and wiping devices arranged to move in toward the opposite sides and the end of the heel portion of the last as the last moves rearwardly and acting to press the upper against the last and to wipe its upstanding edge over 70 upon the innersole, and actuating means for said devices.

18. A machine of the class described having, in combination, means for supporting a last in inverted position with an upper arranged loosely thereon, devices for seizing the upper at the sides of the fore part and straining it lengthwise of the last, means for moving the last and upper-straining devices as an entirety toward the rear of the machine, a plurality of upper-pressing and wiping devices arranged to move in toward the opposite sides and the end of the heel portion of the last and acting to press the upper against the last and to wipe its upstanding edge over 80 upon the innersole, actuating means for said devices, and means to drive fastenings into the overwiped upper.

19. A machine of the class described having, in combination, a jack for supporting a last in inverted position with an upper arranged loosely thereon, a frame supported from said jack and carrying grippers arranged to seize the upper at the toe end and the sides of the fore part and hold it outspread, means for moving said frame to cause the grippers to strain the upper laterally and longitudinally of the last, means for moving said jack and grippers-carrying frame rearwardly while maintaining the 95 strain upon the upper, upper-pressing and wiping devices arranged to press the upper against the two sides and the end of the last and to wipe the upstanding edge of the upper over upon the innersole at said 100 points, and means for moving said devices toward the heel of the last as the last is moved rearwardly.

20. A machine of the class described having, in combination, a jack for supporting a 115 last in inverted position with an upper thereon, a grippers-carrying frame supported from the jack, grippers on said frame arranged to seize the upper at the fore part and strain it lengthwise of the last, means 120 for moving said last and frame rearwardly while the upper is under strain, upper pressing and wiping devices arranged to engage the upper at the two sides and the end of the heel of the last and acting to press the 125 upper against the last and to wipe its upstanding edge down on the innersole, and actuating means to move said devices up to the last as the last is moved rearwardly.

21. A machine of the class described hav- 130

- ing, in combination, a jack for supporting a last in inverted position with an upper thereon, a grippers-carrying frame supported for movements with the jack toward and from the front of the machine, grippers on said frame arranged to seize the upper, means for actuating the frame independently of the jack to strain the upper about the last, means for moving said jack and frame toward the rear of the machine, and means for bending the upper over the heel. 5
22. A machine of the class described having, in combination, a jack for supporting a last in inverted position with an upper thereon, a grippers-carrying frame supported for movements with the jack toward and from the front of the machine, grippers on said frame for seizing the upper, means for actuating the frame independently of the jack to strain the upper about the last, means for moving said jack and frame toward the rear of the machine, and means for bending the upper over the heel seat portion of the last at the two sides 10 and at the back of the heel. 25
23. A machine of the class described having in combination, a jack for supporting a last in inverted position with an upper thereon, a grippers-carrying frame supported for movements with the jack toward and from the front of the machine, grippers on said frame for seizing the upper, means for actuating the frame independently of the jack to strain the upper about the last, 30 means for moving said jack and frame toward the rear of the machine, means for bending the upper over the heel seat portion of the last at the two sides and at the back of the heel, and means for driving 35 fastenings through the bent over portions of the upper. 40
24. A machine of the class described having, in combination, a jack for supporting a last in inverted position with an upper thereon, a grippers-carrying frame supported for movements with the jack toward and from the front of the machine, grippers on said frame for seizing the upper, means for actuating the frame independently of the jack to strain the upper about the last, means for moving said jack and frame toward the rear of the machine, and means for pressing the upper against the last and for wiping its upstanding edge down 45 upon the innersole at the sides and back of the heel. 55
25. A machine of the class described having, in combination, a jack for supporting a last in inverted position with an upper thereon and presented toward the front of the machine, grippers for seizing the upper, means for moving the jack with the last and gripped upper toward the rear of the machine, a down-hold and means for mov- 60
- ing said jack and down-hold in opposite directions to clamp the shoe. 65
26. A machine of the class described having, in combination, a jack for supporting a last in inverted position with an upper thereon and presented toward the front of the machine, grippers arranged for seizing the upper at the fore part and holding it outspread, means for moving the jack with the last and gripped upper toward the rear of the machine, a down-hold, and means for moving said jack and down-hold in reverse directions to clamp the shoe. 70
27. A machine of the class described having, in combination, a jack for supporting a last in inverted position with an upper thereon, grippers for engaging the upper, means for moving the jack with the last and gripped upper from a forwardly-inclined position toward the rear of the machine, a down-hold, and yielding means for moving said jack and down-hold in reverse directions to clamp the shoe. 80
28. A machine of the class described having, in combination, a jack for supporting a last in inverted position with an upper thereon, pivotal means for supporting the jack in a forwardly-inclined position at the front of the machine, a frame carrying grippers for engaging the upper at the fore part of the last, independent pivotal means for supporting said frame, means for moving said jack and frame rearwardly while the grippers engage the upper, a down-hold, and means for reversely moving said jack and down-hold to clamp the last. 90
29. A machine of the class described having, in combination, a jack for supporting a last in inverted position with an upper thereon, a vertically sliding bar pivotally connected with said jack, grippers for engaging the upper, means for moving the jack with the last and gripped upper from a forwardly-inclined position toward the rear of the machine, a lever connected with said bar, a down-hold, connections including a yielding element between said down-hold and lever, and yielding means for actuating said lever to impart movements in reverse directions to the jack and down-hold for clamping and unclamping the last. 105
30. A machine of the class described having, in combination, a jack for supporting a last in inverted position with an upper thereon, means for supporting the jack in a forwardly inclined position, a down-hold, and automatic means for moving said jack rearwardly to position the last beneath said down-hold and for then moving the down-hold and jack reversely through a common connecting member to clamp the last. 120
31. A machine of the class described having, in combination, a jack for supporting 125

- a last in inverted position with an upper thereon, means for supporting the jack in a forwardly inclined position, a down-hold, automatic means for moving said jack beneath the down-hold and for then moving the down-hold and jack reversely to clamp the last, and manually-controlled means for unclamping the last and for returning said jack to its forwardly-inclined position.
- 10 32. A machine of the class described having, in combination, a jack for supporting a last in inverted position with an upper thereon, means for supporting the jack in a forwardly-inclined position, grippers for engaging the upper at the fore part of the last, a down-hold, means for moving the jack rearwardly to position the last beneath the downhold, means for reversely actuating the down-hold and jack to clamp the last, means to wipe the upstanding upper over the heel end of the last, and means to unclamp the last and to then return the jack to the front of the machine.
- 15 33. A machine of the class described having, in combination, a jack for supporting a last in inverted position with an upper thereon, means for supporting the jack in a forwardly-inclined position at the front of the machine, grippers for engaging the upper at the fore part of the last, a down-hold, means for moving the jack rearwardly to position the last beneath the down-hold, means for reversely actuating the down-hold and jack to clamp the last, means to 20 wipe the upstanding upper over the heel end of the last, means to drive fastenings through the overwiped upper, and means to unclamp the last and to return the jack to the front of the machine.
- 25 34. In a machine of the class described, a wiper constructed and arranged to move toward and engage the upper of a shoe at the edge of a last and then to move up and over said edge, and a presser arranged below and supported for rocking movements with said wiper and coöperating therewith to form a well-defined edge on the upper.
- 30 35. In a machine of the class described, a wiper movable toward a last in a plane substantially parallel with the last bottom, and supporting means for said wiper constructed to permit the wiper to move up and over the edge of the last, in combination with a presser located closely adjacent to and supported for rocking movements with said wiper and coöperating therewith to form a well defined edge on the upper.
- 35 36. In a machine of the class described, a wiper movable toward a last in a plane substantially parallel with the last bottom, and supporting means for the wiper permitting it to rock upwardly when it meets the edge of the last, and then to advance over the last bottom, in combination with a yieldingly mounted presser located below and closely adjacent to said wiper and co-operating therewith to shape the upper at the edge of the last.
- 40 37. In a machine of the class described, a wiper movable toward a last, and supporting means for said wiper constructed to permit the wiper to yieldingly move up and over the edge of the last, in combination with a presser located below and immediately adjacent to the wiper and arranged to yield backwardly as the wiper advances over the last bottom.
- 45 38. In a machine of the class described, a wiper, a presser located below and closely adjacent to said wiper and arranged to co-operate with the wiper in forming a sharp edge on the upper about the heel end of the shoe, a common support for said parts permitting the wiper to tilt as it moves up and over the edge of the last, and means permitting the presser to yield backwardly as the wiper advances over the last bottom.
- 50 39. In a machine of the class described, wipers independently supported for movements toward and from the heel end and the two sides of a last and each provided with an aperture, fastening-inserting mechanisms, including drivers, supported for movements with said wipers, and means to actuate said drivers to drive fastenings through said apertures into the overwiped upper.
- 55 40. A machine of the class described having, in combination, a wiper provided with an aperture, means for causing the wiper to move up and over the edge of a last and wipe the upper down upon the last bottom, a presser supported for movements with the wiper, a driver carried by said wiper, means for supplying fastenings, and means for actuating the driver to drive a fastening through said aperture into the overwiped upper.
- 60 41. A machine of the class described having, in combination, a wiper provided with an aperture, means for advancing the wiper over a last to wipe an upper down thereon, staple-forming and driving mechanism, including a driver, supported for movement with said wiper, and actuating means to cause the driver to drive a staple through said aperture into the overwiped upper.
- 65 42. A machine of the class described having, in combination, a wiper provided with an aperture, means for advancing the wiper over a last to wipe an upper down thereon, a driver supported over said aperture, a raceway provided with staple molding surfaces and an anvil, coöperating staple forming devices carried by the driver, staple-strip feeding means connected with said driver, and means for actuating the driver to successively form and feed forward the staples and to drive a staple through said aperture into the overwiped upper.

43. In a machine of the class described, the combination with last and upper positioning means, of means movable relatively to the last to lay the margin of the upper inwardly over the last bottom, and fastening means movable with said overlaying means into position for fastening the upper, said fastening means comprising coöperating members relatively movable to form a fastener between them and a member for forcing said fastener into the upper. 5
44. In a machine of the class described, the combination with last and upper positioning means, of a wiper movable relatively to the last to wipe the margin of the upper inwardly over the last bottom, and fastening means movable with said wiper into position for fastening the margin of the upper, said fastening means comprising a staple 10 driver and mechanism for forming staples and for feeding them into the path of movement of the driver. 15
45. In a machine of the class described, the combination with means for supporting a last with an upper thereon, of separate wipers arranged to move from positions removed from the last up to and over the edge of the last on opposite sides adjacent to the heel breast line, and also at the back 20 of the heel, fastening-inserting mechanisms including drivers carried by said wipers, and a hammer for simultaneously actuating said drivers when the wipers are positioned over the edge of the last. 25
46. In a machine of the class described, the combination with means for supporting a last with an upper thereon, of wipers arranged to move from positions removed from the last to and over the edge of the last on opposite sides adjacent to the heel breast line, and at the back of the heel, pressers carried by said wipers, fastening-inserting mechanisms including drivers movable with said wipers, and a hammer for 30 simultaneously actuating said drivers when the wipers are positioned over the edge of the last. 35
47. In a machine of the class described, a jack, a down-hold for coöperating with said jack in clamping a last, lasting means, fastening-inserting means including a driver, and a driver-actuating hammer guided by said down-hold. 40
48. In a machine of the class described, the combination with means for supporting a shoe, wiping and fastening-inserting mechanisms arranged for operation at the back and at the sides of the heel portion of the shoe, and supporting and actuating means 45 for each of said mechanisms comprising pivoted members arranged to form a parallelogram whereby said mechanisms will be caused to move toward and from the shoe in lines substantially parallel with the shoe bottom. 50
49. In a machine of the class described, the combination with means for supporting a shoe, of a plurality of wipers arranged for operation at the back and at the sides of the heel portion of a shoe, fastening-inserting mechanisms carried by said wipers, links pivotally connecting said mechanisms with the machine frame, levers fulcrumed to the frame and having one arm pivotally connected with the wipers and arranged parallel with the links, a single member yieldingly connected with the other arm of said levers, and means for actuating said member to move said wipers and mechanisms toward and from the shoe. 55
50. In a machine of the class described, the combination with last and upper positioning means, of devices movable inwardly at opposite sides of the last for laying the margin of the upper over the last bottom, upper fastening devices comprising drivers movable inwardly with said overlaying devices into position for driving fasteners into the margin of the upper, and a hammer into operative relation to which said drivers are carried in their inward movement for operating the drivers simultaneously to drive the fasteners. 60
51. In a machine of the class described, a jack for supporting a last in inverted position, a down-hold positioned above the jack and supported for adjustments vertically and lengthwise of the last, and means including a yielding element for operating said down-hold to clamp the last to the jack. 65
52. In a machine of the class described, a jack for supporting a last in inverted position, a plurality of down-holds positioned above the jack in spaced relation longitudinally of the last, said down-holds being independently supported for adjustments vertically and lengthwise of the last, and means including a yielding element for operating said down-holds to clamp the last to the jack. 70
53. A machine of the class described having, in combination, means for supporting a last in inverted position at the front of the machine with an upper thereon, means for gripping the upper at the fore part and for straining it lengthwise of the last, means for moving the jack carrying the last and gripped upper toward the rear of the machine, means for pressing the upper against the sides and end of the heel portion of the last and for wiping the upper and counter flange over upon the innersole, means for clamping the shoe and for bringing the machine to a stop, and means for thereafter restarting the machine, for driving fastenings through the overwiped upper, and for returning the assembled shoe to the front of the machine. 75
54. In a machine of the class described, 80

shoe materials while the bending means retains said materials in position.

66. In an assembling machine, the combination with means for gripping an upper 5 at the toe end of a last and straining it longitudinally of the last, of means for bending the upper and counter over upon the innersole at three separated points located, respectively, at the heel end, and 10 on opposite sides of the heel approximately at the breast line, and means to simultaneously drive fastenings through the bent over shoe materials while the bending means holds said materials in position.
67. In an assembling machine, the combination with means for gripping an upper 15 at the forepart of a last and stretching it longitudinally, of means for pressing the strained upper against the opposite sides 20 of the heel portion of the last and against the rear of the heel, means operatively connected with said pressing means for wiping the upstanding upper over the edge of the last, and means for securing the overwiped 25 upper to the innersole.

68. In a machine of the class described, the combination with a jack, of a back gage, means for moving the jack to position a shoe against said gage, means for pressing 30 the upper against the rear face and the sides of the heel of a last at separated points, and means for wiping separated portions of the upper flange over upon the innersole at those parts of the shoe where 35 said pressure is applied.

69. A machine of the class described having, in combination, means for pulling an upper to draw it about the heel portion of a last, upper fastening means for securing 40 the heel portion of the upper in the correct relation to the last, and power driven means for operating said upper pulling means and for moving the shoe to a different position to present it in operative relation to said 45 fastening means.

70. A machine of the class described having, in combination, means for pulling an upper to draw it about the heel portion of a last, upper fastening means for securing 50 the heel portion of the upper in the correct relation to the last, and power driven means for operating said upper pulling means and for moving the shoe and the upper pulling means together to a different position while 55 the upper is under tension to present the shoe in operative relation to said fastening means.

71. A machine of the class described having, in combination, a gripper for engaging 60 the forepart of an upper on a last, a shoe support for positioning a last and an upper initially in operative relation to said gripper, upper fastening means, and power driven means for operating said gripper to 65 draw the upper about the heel portion of

the last and for moving the shoe support and the gripper together into position for the heel portion of the tensioned upper to be secured in the correct relation to the last by the operation of said fastening means. 70

72. A machine of the class described having, in combination, a shoe support, grippers for engaging an upper at the toe end and at opposite sides of the forepart of a last on said support, power operated means 75 for operating said grippers to stretch the upper longitudinally and laterally and for moving the shoe support and the grippers together into a different position to permit the heel portion of the upper to be secured 80 in the correct relation to the last, and upper fastening means arranged to drive fastenings at the heel end and on opposite sides of the heel portion of the shoe when the shoe is presented in said last named position. 85

73. A machine of the class described having, in combination, means for pulling an upper to draw it about the heel portion of a last, upper fastening means for securing 90 the heel portion of the upper in the correct relation to the last, and power driven means constructed to operate said upper pulling means and to move the shoe into operative 95 relation to said fastening means and subsequently at the will of the operator to cause the fastening means to fasten the upper.

74. In a machine of the class described, a wiper constructed to wipe the margin of an upper over the bottom of a last, a presser member arranged to engage the side of the shoe adjacent to the portion of the stock engaged by said wiper, said wiper and presser member being supported for rocking movement together in response to the resistance 100 encountered by the wiper in wiping the stock over the bottom of the last, and yielding means tending to resist such rocking movement of the wiper and the presser member. 105

75. In a machine of the class described, a wiper constructed to wipe the margin of an upper over the bottom of a last, said wiper being supported for rocking movement in response to the resistance encountered by the wiper in wiping the stock over the bottom of the last, yielding means tending to resist 110 such rocking movement of the wiper, and a presser member for engaging the side of the shoe adjacent to the portion of the stock engaged by said wiper, said presser member 115 being yieldable backwardly relatively to the wiper as the wiper advances over the shoe and mounted also for rocking movement with the wiper. 120

76. In a machine of the class described, 125 the combination with shoe positioning means, of a wiper movable toward a shoe positioned by said means and constructed to wipe the margin of the upper over the bottom of the last, a presser member arranged 130

- the combination with a pivotally mounted jack, of a back-gage, mechanism for moving the jack to position a shoe against said gage, means for pressing the upper against the rear face and the sides of the heel of the last at separated points only, and means for wiping separated portions of the upper flange over upon the innersole at those parts of the shoe where said pressure is applied. 5
- 10 55. In a machine of the class described, the combination with a pivotally mounted jack, of a back-gage, mechanism for moving the jack to position a shoe against said gage, means for pressing the upper against the rear face and the sides of the heel of the last, means for wiping separated portions of the upper flange over upon the innersole at those parts of the shoe where said pressure is applied, and means to drive fastenings through the overwiped upper. 15
- 15 56. In a machine of the class described, the combination with a pivotally mounted jack for supporting a last with an upper thereon, of means for seizing the upper at the fore part and stretching it longitudinally, a back-gage, mechanism for moving the jack to position the heel face of the last against said gage, means for pressing separated portions only of the upper against the rear face and the sides of the heel of the last, and means for wiping separated portions of the upper flange over upon the innersole at those parts of the shoe where said pressure is applied. 20
- 20 57. In a machine of the class described, a back-gage comprising a bar 190 having a heel-engaging part 190^a, a bracket 186, and links 187 and 191 supporting said gage from said bracket, one of said links having an angular portion 186^b provided with a slot, and means in said slot for adjustably securing said link to the bracket. 25
- 25 58. A shoe assembling machine having, in combination, last supporting means, upper pulling means constructed and arranged to strain the upper along the sides of the last and thereby to hold the wings of the heel stiffener in proper relation to the plane of the last bottom, and mechanism for laying the marginal portions of the upper and the stiffener wings over upon the heel seat and fastening the stiffener wings at each side of the last bottom to hold them in position for lasting. 30
- 30 59. In an assembling machine, the combination with means for separately seizing an upper at the toe end and on both sides of the fore part of a last and for holding it in an outspread condition and straining it along the sides of the last, of means for driving fastenings through the upper while under strain at points substantially in line with the heel breast. 35
- 35 60. In an assembling machine, the combination with means for gripping an upper
- at the toe end and on both sides of the fore part of a last and for separately straining it in three directions and holding it in an outspread condition, of means for bending the upper and counter over upon the innersole at substantially the forward ends of the counter, and means for driving fastenings into said bent over portions of the upper and counter. 70
61. In an assembling machine, the combination with means for independently seizing an upper at the end and on opposite sides of the fore part of a last and holding it in an outspread condition and strained along the sides of the last, of means for pressing the upper against the sides of the heel end portion of the last while it is under lengthwise strain and for bending the upstanding portions of the upper over upon the last, and means for driving fastenings 75 into the bent over portions of the upper. 80
62. In an assembling machine, the combination with means for gripping an upper at the toe end of a last and straining it lengthwise of the last, of means for pressing individual, separated portions of the upper against the sides of the last at the ends of the counter and for bending the upper and counter over upon the innersole at said points, and means for driving fastenings 85 through said bent over portions. 90
63. In an assembling machine, the combination with means for gripping an upper at the toe end of a last and straining it lengthwise of the last, of means for pressing the upper against the last at three separated points located, respectively, at the heel end, and on opposite sides of the last substantially at the ends of the counter and for bending the upper and counter over upon the innersole at said points, and means for driving a fastening through the bent over shoe materials at each of said points. 100
64. In an assembling machine, the combination with means for gripping an upper at the toe end of a last and straining it lengthwise of the last, of means for pressing separated individual portions of the upper against the sides of the last at the ends of the counter and for bending the upper and counter over upon the innersole at said points, and means for driving fastenings 105 through the bent over materials while the bending means holds said materials in position. 110
65. In an assembling machine, the combination with means for gripping an upper at the toe end of a last and straining it longitudinally of the last, of means for pressing the upper against the last at the heel end and on opposite sides of the heel substantially at the breast line and for bending the upper and counter over upon the innersole at said points, and means for driving fastenings 115 through the bent over 120
- 125

- to engage the side of the shoe adjacent to the portion of the stock engaged by said wiper, said wiper and said presser member being supported for rocking movement together in response to the resistance encountered by the wiper in wiping the stock over the bottom of the last, and fastener driving mechanism movable toward the shoe with said wiper and presser member.
- 10 77. In a machine of the class described, the combination with shoe positioning means, of a wiper mounted for movement toward a shoe positioned by said means and constructed to wipe the margin of the upper over the bottom of the last, a presser member arranged to engage the side of the shoe adjacent to the portion of the stock engaged by said wiper, said wiper and presser member being supported for rocking movement together in response to the resistance encountered by the wiper in wiping the stock over the bottom of the last, and staple forming and driving mechanism movable toward the shoe with said wiper and presser member into position for driving a staple through the overwiped upper.
- 15 78. In a machine of the class described, the combination with means for supporting a last and an upper, of a wiper constructed to wipe the margin of the upper over the bottom of the last, means comprising parallel links for supporting said wiper for movement toward and from the shoe in substantially parallel relation to the plane of the shoe bottom, and a connection between said wiper and its supporting means constructed to permit the wiper to yield in a direction transverse to the plane of the shoe bottom in response to the resistance of the shoe materials.
- 20 79. In a machine of the class described, the combination with shoe positioning means, of a wiper constructed to wipe the margin of the upper inwardly, and means comprising substantially parallel links for supporting said wiper for movement toward and from the shoe while tending to maintain it in substantially uniform angular relation to the plane of the shoe bottom, the wiper being so mounted upon its supporting means as to permit it to yield in a direction transverse to the plane of the shoe bottom in response to resistance of the shoe materials.
- 25 80. In a machine of the class described, the combination with shoe positioning means, of a wiper constructed to wipe the margin of the upper inwardly, and means comprising substantially parallel links for supporting said wiper for movement toward and from the shoe while tending to maintain it in substantially uniform angular relation to the plane of the shoe bottom, the wiper being pivotally mounted on said supporting means to swing yieldingly about an axis extending in substantially parallel relation to the plane of the shoe bottom, and spring means tending to resist such swinging movement of the wiper.
- 30 81. In a machine of the class described, the combination with shoe positioning means, of a wiper constructed to wipe the margin of the upper inwardly, a wiper support movable toward the shoe to operate the wiper, spring means for positioning the wiper in such relation to said support and to the shoe as to cause the wiper in its inward wiping movement to be deflected by resistance of the upper at the edge of the shoe bottom, and means arranged for use at the will of the operator to adjust the wiper in the direction in which it would be thus deflected and to hold it automatically in adjusted position.
- 35 82. In a machine of the class described, the combination with last and upper positioning means, of a member for laying the margin of the upper over the bottom of the last, a support for said member, means for operating said support to carry the member into engagement with the upper and inwardly over the last bottom, said member being pivotally mounted on the support to permit it to swing about an axis extending in substantially parallel relation to the plane of the last bottom, yieldable means tending to swing the member in one direction about its axis to cause it to press upon the margin of the upper, and additional means for adjusting said member in the opposite direction about its axis.
- 40 83. In a machine of the class described, the combination with shoe positioning means, of an overlaying member, a support for said member relatively to which the member is mounted to swing in directions transverse to the plane of the shoe bottom, means for moving said support toward the shoe to operate said member, spring means tending to swing said member in a direction to cause it to press the upper materials upon the shoe bottom, and an adjustable stop co-operating with said spring means to determine a normal position of said member.
- 45 84. In a machine of the class described, the combination with last and upper positioning means, of a wiper for wiping the margin of the upper over the bottom of the last, spring means for positioning the wiper in such relation to the plane of the last bottom as to cause it to be moved in a direction transverse to said plane in the overwiping operation by the resistance of the shoe materials, and means arranged for use at the will of the operator to position and to hold the wiper automatically against the tension

of said spring means in such relation to the plane of the last bottom as to permit it to operate with decreased resistance.

85. In a machine of the class described, 5 the combination with last and upper positioning means, of a wiper for wiping the margin of the upper over the bottom of the last, a support for said wiper movable toward the shoe to operate the wiper, said 10 wiper being so mounted on its support as to permit it to tip relatively to the support in directions transverse to the plane of the last bottom, a spring tending to tip said wiper in a direction for applying pressure to the 15 shoe materials on the last bottom, and adjusting means arranged for use at the will of the operator to tip the wiper in the opposite direction against the tension of said spring and to hold it in a determined angular relation to its support.
86. In a machine of the class described, 20 the combination with last and upper positioning means, of wipers movable relatively to the last to engage the margin of the upper locally at the end and at opposite sides of 25 the end portion of the last and wipe it inwardly over the last bottom, fastening mechanisms including drivers movable with said wipers into position for driving fasteners 30 into the overwiped margin of the upper, and a common driver operating member into operative relation to which said drivers are carried by their inward movement with the wipers.
87. In a machine of the class described, 35

the combination with shoe positioning means, of overlaying means mounted for movement toward and from the shoe in directions substantially parallel to the plane of the shoe bottom, fastener forming means mounted 40 for movement toward and from the shoe in directions substantially parallel to the plane of the shoe bottom, fastener forming means mounted for movement toward and from the shoe with said overlaying means, and 45 a fastener driver also movable with said overlaying means to position it relatively to the shoe, said driver being movable in a direction transverse to the plane of the shoe bottom to drive the fastener. 50

88. In a machine of the class described, the combination with shoe positioning means, of a wiper mounted for movement toward and from the shoe in directions substantially parallel to the plane of the shoe bottom, a 55 staple driver mounted for positioning movement with said wiper, staple forming means comprising coöperating relatively movable forming members also mounted for movement with the wiper, and means for operating said driver to drive a staple after the driver has been moved with the wiper to operative position.

In testimony whereof I have signed my name to this specification in the presence of 60 two subscribing witnesses.

JESS. S. WENTWORTH.

Witnesses:

DON C. McCLELLAN,
RAY A. BAUMANN.

It is hereby certified that in Letters Patent No. 1,336,875, granted April 13, 1920, upon the application of Jesse S. Wentworth, of Decatur, Illinois, for an improvement in "Assembling-Machines," errors appear in the printed specification requiring correction as follows: Page 8, line 15, for the word "last" read *upper*; page 10, line 74, claim 8, for the word "of," third occurrence, read *for*; page 18, line 41, claim 87, beginning with the word "in" strike out all to and including the word "shoe," line 45; and that the said Letters Patent should be read with these corrections therein that the same may conform to the record of the case in the Patent Office.

Signed and sealed this 14th day of September, A. D., 1920.

[SEAL.]

M. H. COULSTON,

Acting Commissioner of Patents

Cl. 12—2.
